UNITED STATES PATENT OFFICE.

ARTHUR A. MCKAIN AND WILLIAM SEBURN, OF INDIANAPOLIS, INDIANA.

PNEUMATIC STRAW-STACKER.

SPECIFICATION forming part of Letters Patent No. 518,620, dated April 24, 1894.

Application filed December 27, 1893. Serial No. 494,830. (No model.)

To all whom it may concern:

Be it known that we, ARTHUR A. MCKAIN and WILLIAM SEBURN, citizens of the United States, residing at Indianapolis, in the county of Marion and State of Indiana, have invented 5 certain new and useful Improvements in Pneumatic Straw-Stackers, of which the following is a specification.

Our said invention consists in certain improvements upon that class of machines known as "pneumatic straw elevators and stackers," of which that shown and described in Letters Patent No. 467,476, to James Buchanan, dated January 19, 1892, is a leading example.

The object of our said invention is to provide a means whereby the trunk or chute may be elevated to the position which it should occupy in use, and depressed to the position which it should occupy when not in use, without employing the flexible joint which has heretofore been necessary. This object is accomplished by seating the turn-table upon an incline of such an angle that when the chute 25 or trunk is swung out into the position it occupies when in use, extending over the stack, it is elevated to a considerable height; and when swung around over the machine, in the position it occupies when the machine is out 30 of use, or is being transported from place to place, it is in nearly (and may be in quite) a level position.

Referring to the accompanying drawings which are made a part hereof, and on which 35 similar letters of reference indicate similar parts, Figure 1 is a view of the rear end of a thrashing machine, having a pneumatic straw elevator and stacker attached thereto, embodying our said invention, the position of 40 the trunk or chute when in use being shown in full lines, and the position when folded, or out of use, being shown in dotted lines. Fig. 2 is a fragmentary view similar to a portion of Fig. 1, but on an enlarged scale, showing the turn-table and supporting frame and 45 braces more clearly. Fig. 3 is a horizontal sectional view, as seen when looking downwardly from the dotted line 3 3 in Fig. 2, and Fig. 4 a detail sectional view on the dotted 50 line 4 4 in Fig. 3.

In said drawings the portions marked A represent the body of the thrashing machine; B

the fan; C the turn-table; D the trunk or chute, and E the hood or mouth portion thereof. The general construction of these several parts is 55 in many respects similar to those shown in the above mentioned Letters Patent, except that they are generally somewhat simplified. The thrashing machine A is or may be of any ordinary construction, except that it is provided with an inclined platform A' upon the rear end, to which the turn-table C is attached. The fan B is within the usual fan casing B', and arranged in a similar manner to that heretofore used. The turn-table C is 60 secured to the inclined platform A' by means of housings A², containing anti-friction trucks a' a² and a³, which bear against the inner, upper, and lower surfaces thereof, as shown most plainly in Figs. 3 and 4. The outer edge 65 of this turn-table is a screw gear with which the worm C' on the shaft C² engages, and whereby said turn-table is revolved. The trunk or chute D is similar to that shown in the above-mentioned Letters Patent, except 70 that it is a continuous rigid structure having no joint at the lower end;—such a joint having heretofore been employed at about the point where the yoke frame D' is located. Said trunk is secured to the turn-table C by 75 the brace bars C³ C⁴ C⁵ C⁶, which unite it firmly and rigidly to said turn-table. A comparatively long stay rod D² runs from the top of the yoke frame D' to a point toward 80 the front end of the chute, and thus sustains 85 said chute strongly in place. The hood or mouth-piece E is secured to the outer end of the trunk D, and is hinged thereto at e, as is usual. It is operated by a rod E' and a handle E², in a manner similar to that in which 90 such parts have previously been operated.

Having thus fully described our said invention, what we claim as new, and desire to secure by Letters Patent, is—

1. The combination, of the thrashing machine provided with the platform A' having its highest side at the rear end of the machine, a turn-table secured theron, and parallel therewith, a straw elevator trunk or chute D secured to said turn-table, and means for revolving said turn-table, whereby said straw elevator trunk is caused to be elevated in its extended position and to be lowered when in its folded up position above the body of the 95 100

thrashing machine, substantially as shown and described and for the purposes specified.

2. The combination of the thrashing machine having the inclined platform A' with its highest side at the rear end of the machine, the turn-table C mounted thereon, and parallel therewith, the rigidly constructed straw elevator trunk or chute secured to said platform by the braces C³ C⁴ C⁵ and C⁶, the 5 housings and trucks securing said turn-table to the platform, and the shaft and worm gear for revolving said turn-table, the whole being constructed and operating substantially as shown and described.
- 10 3. The combination of the thrashing machine having an inclined platform, a turn- 15

table mounted on said platform, and parallel therewith, a rigid straw stacker trunk or chute mounted on said turn-table and secured thereto by means of braces and frame pieces, as 20 C' C² C³ C⁴, thus securing said elevator trunk or chute rigidly thereto, substantially as set forth.

In witness whereof we have hereunto set our hands and seals, at Indianapolis, Indiana, this 25 16th day of December, A. D. 1893.

ARTHUR A. MCKAIN. [L. S.]
WM. SEBURN. [L. S.]
